(57) **CLAIM**

The ornamental design for a surgical instrument, as shown and described.

DESCRIPTION

1.-4. Surgical instrument

1.1 : Front

1.2 : Back

1.3 : Left

1.4 : Right

1.5 : Top

1.6 : Bottom

1.7 : Perspective

2.1 : Front

2.2 : Back

2.3 : Left

2.4 : Right

2.5 : Top

2.6 : Bottom

2.7 : Perspective

3.1 : Front

3.2 : Back

3.3 : Left

3.4 : Right

3.5 : Top

3.6 : Bottom

3.7 : Perspective

4.1 : Front

4.2 : Back

4.3 : Left

4.4 : Right

4.5 : Top

4.6 : Bottom

4.7 : Perspective

The dashed lines in reproductions 2.1 through 2.7 depict portions of the surgical instrument that form no part of the claim. The low-contrast portions of the renderings in reproductions 4.1 through 4.7 depict portions of the surgical instrument that form no part of the claim.

1 Claim, 28 Drawing Sheets
